UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

SHELF BOX.

Application filed July 26, 1920. Serial No. 398,999.

To all whom it may concern:

Be it known that I, WALTER N. VANCE, a citizen of the United States, residing in Chicago Heights, in the county of Cook 5 and State of Illinois, have invented a new and useful Improvement in Shelf Boxes, of which the following is a specification.

This invention relates in general to boxes and has more particular reference to metal 10 boxes constructed for use as shelf boxes and for similar purposes.

The principal object of the present invention is the provision of a metal shelf box wherein partitions may be easily and quickly 15 inserted or assembled in a locked position and removed and this without the provision of special locking members or parts provided upon the box or upon the partition.

Another important object of the invention 20 is the provision of such a construction in which the partition or partitions when in position will be positively and firmly pressed down against the box bottom to prevent small articles passing beneath or engaging 25 beneath the partition.

Another important object of the invention is the effectuation of certain improvements in box construction as will be later apparent 30 as the invention is more fully described.

Another important object of the invention 35 is the provision of novel and improved label holding means and this without the addition of any parts or members for the purpose.

Another and highly important object of 40 the invention is the provision of a hand-hold of new and improved construction and arrangement with respect to the box of which it forms a part.

Numerous other objects of the invention 45 will be apparent as it is better understood from the following description which taken in connection with the accompanying drawing discloses a preferred embodiment thereof:

Referring to the drawing,

Figure 1 is a perspective view of a shelf box embodying my present invention;

Fig. 2 is a similar view of the partition;

Fig. 3 is a section taken longitudinally 50 through such shelf box;

Fig. 4 is a section on the line 4—4 of Fig. 3;

Fig. 5 is an end elevation thereof; and

Fig. 6 is an enlarged detail of the notch or recess construction provided in the present instance in the side flanges. 55

The box shown on the drawing is of the character of that described and claimed in my application Serial No. 301,985 filed June 5, 1919, for metal boxes and in some respects 60 the present invention constitutes improvements thereupon.

For the purpose of illustrating my present invention I have shown on the drawing in Fig. 1 a sheet metal shelf box comprising side walls 11, front end wall 12, rear end wall 13 and bottom wall 14. The side and bottom walls are formed of a single sheet of metal bent on lines of bend 15 into the box form shown. The side walls are provided with end flaps or flanges 16 and the bottom wall with end flaps or flanges 17. These flanges are folded over on to the outer faces of the end walls and are mitred at 18 at adjacent ends. The extremities of the flanges 16 at the front are offset at 19 to provide outer label holding parts 21 which provide channels 22 between themselves and the front wall 12 into which a label may be inserted. The side flanges 16 70 back of the offset parts 19 are secured as by welding, spot welding or otherwise to the outer face of the front wall 12. The central part 23 of the front bottom flange 17 near the line of bend between this flange and the bottom body is offset as at 24, and the extremity 25 of the flange is also offset and in the plane of the part 23. The end parts of the flange 17 are not offset and are fastened in suitable fashion to the end wall. The offset part 23 is provided with one or 75 more apertures 26 extending through it. This aperture or apertures provides a recess or recesses for retaining a hand-hold 27 in position. This hand-hold is bent at 28 to provide a part 29 adapted for insertion between the offset part of the flange 17 and the front wall, and the part 29 of the hand-hold is provided with bosses or outwardly 80 extending protuberances 31 adapted to enter into the recesses or apertures 26 of the flange. The number and arrangement of the bosses correspond to the number and arrangement of the recesses 26. The material of the hand-hold extends outwardly 85 from the line of bend 28 and downwardly as

indicated at 32 the edge 33 being folded back upon itself at 34.

Projections 41 are formed across the lines of bend 15 at the junction of the bottom and side walls which projections are of V-shape sides and arranged at intervals lengthwise of the lines of fold 15. At the top the side walls are provided with downwardly extending flanges 42 spaced inwardly of the side wall bodies. Recesses 43 are provided in the edges of the flanges 42 and arranged one above each projection or protuberance 41 at the bottom of the side walls. One of these recesses is shown on an enlarged scale in Fig. 6 from which it will be noted that each recess comprises a portion 44 deeper than the rest and a second portion 45 smaller and shallower than the portion 44, said portions 44 and 45 being connected by an inclined surface or cam 46, the purpose of which recesses will be more apparent presently.

One or more partitions indicated at 47 are provided and each consists of a metal sheet having side flanges 48 and a bottom flange 49 extending out at right angles to the plane of the partition. The adjoining edges of the bottom and side flanges are cut away at 51 to fit over the protuberances 41 as will be presently described. At the top the partition is bent to provide a round or curved edge 52 the top of which is preferably located at or about the top of the flanges 48.

35 This partition is adapted to be assembled by inserting it within the box and tilting it to bring the curled edge 52 into the larger portions 44 of opposite recesses 43. It is then swung down about the upper edge as 40 a pivotal axis to bring the recesses or openings 51 in the side and bottom flanges over and in registration with the projections or protuberances 41 already mentioned and located just beneath the recesses 43 in which 45 the partition is engaged. The partition is then moved vertically downwardly to engage such protuberances in the recesses 51 to form a bottom holding means for the partition. Thereafter the partition is 50 moved tiltingly or pivotally about its bottom edge the upper edge of the partition sliding over the cam or incline and springing into the portions 45 of the recesses. The side of the recess forming a retaining 55 shoulder for locking the partition in upright position. Thus arranged the overhanging flanges 42 are disposed on the outside of the upper ends of the side flanges 48 of the partition. It is thought that the invention and many of its attendant advantages will be better understood from the foregoing description and it will be apparent that various changes may be made in the form, construction and arrangement of 60 the parts without departing from the spirit 65

and scope of the invention or sacrificing all of its material advantages, the form hereinbefore described being merely a preferred embodiment thereof.

I claim:

1. A box and partition therefor, said box comprising partition holding means at the top and bottom and said partition being of unitary construction adapted to be tilted alternately about its opposite edges in being positioned. 70

2. A box and partition therefor, said box comprising partition holding means at the top and bottom and said partition being adapted to be tilted alternately about its opposite edges in being positioned, and said partition and said means having cam surfaces interengaged during the positioning of said partition. 80

3. A box and partition therefor, said box comprising holding means engaging the partition when the partition is in position in said box, said holding means automatically latching said partition in place upon movement of the partition to proper assembled position. 85

4. A box and partition therefor, said box comprising holding means engaging the partition when the partition is in position in said box, said holding means comprising an inclined cam surface and a stop shoulder and said partition sliding over the cam surface and into position behind the stop shoulder in assembling. 95

5. A box and partition therefor, said box comprising holding means engaging the partition when the partition is in position in said box, said holding means comprising a fixed latch past which the partition is permitted to move by reason of the resiliency of the parts into assembled and secured position. 100

6. A box and partition therefor, said box having parts for engaging the bottom of the partition and overhanging flanges provided with cam recesses at the top for engaging the top of said partition said parts and recesses having fixed position and being adapted to permit positioning of said partition. 110

7. A box and partition therefor, said box having parts for engaging the bottom of the partition and overhanging flanges provided with recesses at the top for engaging the top of said partition, movement of the partition in said recesses and about the bottom engagement locking said partition in position. 115

8. A box and partition therefor, said box having means at the bottom for pivotally engaging the bottom of the partition and means near the top of the box for automatically locking such partition in position after pivotal movement about the bottom. 125

9. A box and partition therefor, said box having overhanging flanges provided with 130

recesses at the top and in which an edge of the partition may be engaged for pivotal movement to swing it about an axis near its upper edge and to let the bottom edge come into assembled position, said recesses having portions in which the upper part of the partition may be engaged to hold such partition in position.

10. A box and partition therefor, said box having an overhanging flange provided with multiple part recesses in which the upper edge of the partition may be inserted and moved in positioning, said recesses also serving by engagement with the partition 15 to hold such partition in place.

11. A box and partition therefor, said box having overhanging flanges provided with recesses for engagement with the partition and provided with recesses, each of such recesses having a portion adapted to permit pivotal movement of the lower edge of the partition and a portion holding said partition in place.

12. A box and partition therefor, said box 25 having overhanging flanges provided with recesses for engagement with the partition and provided with recesses each of such recesses having a portion adapted to permit pivotal movement of the lower edge of the 30 partition and a portion holding said partition in place; said portions being connected by an inclined surface over which the partition slides in moving from the one position to the other.

35. 13. A box and partition therefor, said box comprising overhanging flanges at the top and said partition having parts engaging behind such flanges, and said flanges being provided with multiple part recesses within 40 which said partition may move from unlocked to a locked position.

14. A box and partition therefor, said box comprising means engageable by the partition upon tilting of the partition, means 45 engageable by the partition upon subsequent vertical movement of the partition and

means engageable by the partition upon subsequent tilting movement thereof.

15. A box comprising front and back walls, side and bottom walls connecting the same and having flanges overhanging the front wall and secured thereto said flanges being offset adjacent their edges to provide for the reception of a label.

16. A box comprising front and back 55 walls and side and bottom walls connecting the same and having flanges extending over the front wall in mitred relation and secured thereto, said flanges being offset adjacent their edges to provide for the reception 60 of a label.

17. A box comprising end walls, side and bottom walls connecting the same and having flanges extending over the end walls and secured thereto, said flanges being offset adjacent their edges and a hand-hold having an edge inserted behind one of said offset edges.

18. A box comprising front and back 70 walls, side and bottom walls connecting the same and having flanges extending over the front walls and secured thereto, said flanges being offset adjacent their edges and a hand-hold inserted behind the bottom flange, said side flanges providing for the reception 75 of a label.

19. A box, comprising end walls, and side and bottom walls, said bottom wall having a flange extending up and in front of the front end wall and provided with recesses 80 extending from the inner face of said flange, and a hand-hold having a part inserted behind said flange adapted to be secured by portions in engagement in said recesses.

20. A box comprising end walls and side 85 and bottom walls, said bottom wall having a flange extending up in front of the front end wall and provided with apertures extending through it, and a hand-hold having a part inserted behind such flange and secured by portions inserted in said apertures.

WALTER N. VANCE.
